UNITED STATES PATENT OFFICE

2,557,221

SHAVING CREAM APPLICATOR

Antoine Gazda, Providence, R. I.

Application May 5, 1947, Serial No. 746,079

4 Claims. (Cl. 128—65)

1

This invention relates to an improved massage applicator which is designed to be readily attached the threading nipple of a collapsible tube which functions as a handle for the applicator and also as a source of supply for the shaving cream to the massage surface of the applicator.

An object of the invention is to provide an improved structure which will massage the surface to which the applicator is applied and at the same time work up the soap cream into a lather.

A further object of the invention is to provide a port in the applicator for the shaving cream which is self-sealing so that when not in use the contents of the collapsible tube are not exposed to the atmosphere.

A further object of the invention is to provide an applicator constructed from a material such as soft rubber with undulations therein so that it may also function as a brush without any of the disadvantages from the sanitary viewpoint of the usual bristle brush.

It is also an object of the invention to provide a construction which is very economical in that there is no waste of the shaving cream since only the exact quantities used are dispensed.

A still further object is to eliminate the usual waste incident when shaving cream is applied by hand and also avoids the messiness due to such method of applying shaving cream.

With the above and other objects in view which will become apparent from the detailed description below the new and improved massage applicator is shown in the drawings in which:

Fig. 1 is a side elevational view showing the applicator attached to a collapsible tube.

Fig. 2 is a front elevational view of the applicator with a partial showing of the collapsible tube.

Fig. 3 is a sectional view taken on section line 3—3 of Fig. 2.

Fig. 4 is a bottom plan view of the massage applicator.

Fig. 5 is a top plan view thereof, and

Fig. 6 is a perspective view showing the manner in which the applicator may be used.

In the drawings similar reference characters apply to like parts in the various views.

A collapsible tube 5 of the usual type containing a source of supply such as shaving cream has a threaded nipple 6 from which the usual cap has been removed and replaced by the massage applicator indicated generally at 7.

The applicator 7 is preferably constructed of soft rubber and is moulded in the shape shown in the drawings with a downwardly extending

2

projection 8 which contains a threaded socket 9 designed to be screwed upon the nipple 6 so as to make a tight fit therewith. Extending upwardly for a short distance from the socket 9 is a slot 10 which is relatively wide and the slot 10 in turn communicates with a narrower slot 11. The slot 11 as shown in Fig. 5 extends throughout the greater portion of the massage surface 12 of the applicator at substantially the longitudinal center thereof.

The massage surface 12 of the applicator extends at a slight angle approximately 20 to 35° to the longitudinal axis of the collapsible tube and the socket 9 of the applicator. The surface 15 12 is also formed with a plurality of undulations or ribs 13 as is clearly apparent from Fig. 2. In the drawings the ribs 13 are spaced from one another by the grooves 14 and the edges are all shown as being right angular. However it is obvious 20 that the configuration of the ribs 13 and the grooves 14 may be modified in various ways in order to accomplish the functions desired. If desired all the edges may be rounded and the depth of the grooves and the length of the ribs 25 13 may be smaller or greater than that shown provided the desired massaging action is obtained.

Also the projection 8 which does not enter into the massaging action may be constructed of somewhat harder rubber or other material thereby securing a better closure between the applicator 30 and the collapsible tube.

In use the user grasps the collapsible tube 5 as shown in Fig. 6 with the massaging surface 12 in alignment with the surface to which the applicator is applied and by slightly compressing the tube 5 shaving cream is extruded through the nipple 6 into the recess 10 and then spreads out in the slot 11 throughout substantially the entire length of the applicator. From such point the 35 shaving cream is applied to the surface to be lathered and at the same time such surface is massaged by the ribs 12 and the shaving cream worked into a lather. The entire operation is carried out without wasting any of the shaving 40 cream or having the cream applied to surfaces where it is not desired. Upon release of pressure feed of the shaving cream is stopped and then the side walls of the slot 11 collapse and seal the contents of the tube 5 from the atmosphere.

50 I claim:

1. A massage and cream applicator adapted to be secured to the discharge nozzle of a collapsible tube containing a supply of shaving cream comprising a substantially rectangular head portion 55 of soft rubber capable of maintaining substan-

tionally its shape during use having undulations extending transversely of the major axis of said head portion, said undulations being flexible to secure a massaging action, said head portion having a feed slot extending along said axis communicating with said undulations, said head portion having a harder portion thereon and means in said harder portion for securing said head firmly to said tube with said feed slot in communication with said nozzle.

2. A massage and cream applicator adapted to be secured to the discharge nozzle of a collapsible tube containing a supply of shaving cream comprising a substantially rectangular head portion of soft rubber capable of maintaining substantially its shape during use having a series of flexible ribs forming grooves extending transversely of the major axis of said head portion, said head portion having a slot therein extending parallel to said axis in communication with said grooves, a projection upon said head portion of harder material, means upon said projection for securing said head portion to said discharge nozzle and said head portion having a second slot therein of less width than said first mentioned slot interconnecting said first mentioned slot and said nozzle.

3. A massage and cream applicator adapted to be secured to the discharge nozzle of a collapsible tube containing a supply of shaving cream comprising a substantially rectangular head portion of soft rubber capable of maintaining substantially its shape during use having a series of flexible ribs forming grooves extending transversely of the major axis of said head portion, said head portion having a slot therein extending parallel to said axis in communication with said grooves,

5 a projection upon said head portion of harder material, a threaded socket in said projection for securing said head portion to said discharge nozzle and said head portion having a second slot therein interconnecting said first mentioned slot and said nozzle.

10 4. A massage and cream applicator adapted to be secured to the discharge nozzle of a collapsible tube containing a supply of shaving cream comprising a substantially rectangular head portion of soft rubber capable of maintaining substantially its shape during use having a series of flexible ribs forming grooves extending transversely of the major axis of said head portion and at an angle 15 to the longitudinal axis of said collapsible tube, said head portion having a slot therein extending parallel to said axis in communication with said grooves, a projection upon said head portion of harder material, means upon said projection for securing said head portion to said discharge nozzle and said head portion having a second slot therein of less width than said first mentioned slot interconnecting said first mentioned slot and said nozzle.
